UNITED STATES PATENT OFFICE

150,247

DESIGN FOR A BEAUTY SALON DRYING LOUNGE

Sunshine Nichols, Miami Beach, Fla.

Application October 15, 1946, Serial No. 133,972

Term of patent 14 years

(Cl. D15—11)

To all whom it may concern:

Be it known that I, Sunshine Nichols, a citizen of the United States, residing at Miami Beach, in the county of Dade and State of Florida, have invented a new, original, and ornamental Design for Beauty Salon Drying Lounge, of which the following is a specification, reference being had to the accompanying drawing, forming part thereof.

In the drawings:

The dominant features of my design reside in the portions shown in full lines.

I claim:

The ornamental design for a beauty salon drying lounge, as shown and described.

SUNSHINE NICHOLS.
